UNITED STATES PATENT OFFICE.

SOLOMON GERMAN, OF MONKTON, MARYLAND.

WATER-TOWER AND ELEVATOR.

No. 895,008.

Specification of Letters Patent.

Patented Aug. 4, 1908.

Application filed June 4, 1907. Serial No. 377,225.

To all whom it may concern:

Be it known that I, SOLOMON GERMAN, citizen of the United States, residing at Monkton, in the county of Baltimore and State of Maryland, have invented certain new and useful Improvements in Water-Towers and Elevators, of which the following is a specification.

This invention relates to fire extinguishing apparatus and particularly to a combined water tower and elevator, designed not only to be used for the same purposes for which the ordinary and heretofore constructed water towers are intended, to wit, directing a stream of water on a burning building or the like, from an elevated point of vantage, but also useful in elevating the firemen to the upper stories of burning buildings without the use or necessity of ladders or ladder trucks, and adapted also to carry up to the said upper floors or windows of a burning building, a flexible ladder or ladders and one or more lines of hose in addition to the ordinary swivel and main nozzle, thereby combining in the one apparatus many and diversified useful features, and doing away not only with the cost of purchasing and maintaining several apparatus, but also avoiding the interference which is often an incident to the successful fighting of flames, where several independent or separate pieces of fire apparatus obstruct one another in their proper work.

The invention consists in certain constructions, arrangements, and combinations of parts that I shall hereinafter fully describe and then point out the novel features in the appended claims.

For a full understanding of the invention and the merits thereof and also to acquire a knowledge of the details of construction of the means for effecting the result, reference is to be had to the following description and accompanying drawings, in which:

Figure 1 is a perspective view of one form or embodiment of my invention, the water tower and elevator being shown in extended position. Fig. 2 is a similar view of the apparatus in retracted or lowered condition. Fig. 3 is an enlarged vertical sectional view, with parts in side elevation, and other parts broken away, of the tower and elevator. Fig. 4 is a detail sectional view illustrating the automatic interlocking joint between two adjacent telescoping tubes of the tower. Fig. 5 is a detail horizontal sectional view on

the line 5—5 of Fig. 4. Fig. 6 is a detail vertical sectional view illustrating a slightly modified construction of the automatic interlocking joint. Fig. 7 is a detail view illustrating a modified form of tower that may be employed, and which is hereinafter specifically referred to.

Corresponding and like parts are referred to in the following description and indicated in all the views of the drawings by the same reference characters.

My water tower and fireman's elevator combined, comprises a plurality of telescoping tubular sections 1 of any desired number, diameter and length, the several sections being provided at their lower ends with suitable packing, either of a permanent, detachable, or adjustable character, designed to secure a non-leaking joint. It is intended that the tower shall be extended by some fluid motive power, either air, or water, preferably the latter, and for this purpose the base section of the tower is provided with any desired number of couplings 3, to which hose or other flexible connections may be attached leading from the water plug or other similar source of supply, and from a water or other motor, as may be desired. Preferably two or more of these pipe couplings 3 are provided, so that one source of power may be utilized if another should prove deficient or unavailable.

The uppermost section of the tower carries a valved plug or similar cut-off 4 and a preferably metallic swivel nozzle 5 above the said valve, said nozzle being adapted to serve the purpose of the usual water tower and nozzle, and being susceptible of being turned and remaining stationary in any adjusted position so as to direct the stream of water on the flames from an elevated point. In addition to the main nozzle 5, the upper section 1 may also carry a laterally extending pipe coupling 6 to which a flexible section 100 of hose 7 may be attached, said section carrying a nozzle 8 which may be manipulated by one or more firemen standing on the platform hereinafter described. In order to permit the tower to be lowered, one of the sections, preferably the base section, is provided with a drain cock 9.

Each section 1 carries at its upper end a collar 10, screwed or otherwise secured thereto, and each collar is formed with a ball race 110 in which a series of balls or other anti-friction devices 11 is mounted, so as to bear against

the next adjacent section and reduce the friction to a minimum.

In order to automatically lock the several sections securely in extended position, I provide a series of automatically acting locking devices which may be of any desired number and construction, and which in the present instance are in the form of locking blocks 13, carried within recesses in the respective collars 10, and adapted to be automatically pressed out in the recesses 12 in the tubular sections 1 when the respective sections reach the limit of their extension movement. These blocks 13 may be two in number, for each collar, and may be located at diametrically opposite points, and may be pressed inwardly by means of substantial coil springs 15, encircling the outwardly projecting stems 14 that are secured to the blocks 13, and that project outwardly through the collar as shown. The stems 14 are provided at their outer ends with handles, by which the locking devices may be retracted to permit the depression of the tower and elevator.

If desired, I may employ, as a slightly modified form of these automatic locking devices, an annular spring 13^a fitting in an annular recess in the inner section of two sections at a joint, and adapted to pass and snap outwardly over screws 14^a which project inwardly through the collar. In order that the several sections may be held at different adjusted points with respect to each other, that is, before the limit of extension shall have been reached, I may provide a pair of clamps 16 in the collar 10 at diametrically opposite points between the automatic locking devices, said clamps being provided with swiveled adjusting screws 17 projecting inwardly through the collar, as best seen in Fig. 5, and being also preferably roughened on their inner faces, and curved to extend partially around the inner section of tower so as to provide a secure and broad bearing surface for the clamping action.

In order that the apparatus may respond quickly to a fire, it being intended that it shall answer the first alarm, rather than be used as an emergency apparatus, the apparatus is mounted upon a wheeled vehicle 18 which is preferably of the "low down" variety, with the bed projecting sidewise over the traveling wheels. The base or lowermost section 1 of the tower is formed with a ball head 19, fitting within the socket piece 20 that is fastened to the bed of the vehicle in any desired way, this ball and socket connection or mounting of the tower and elevator on the vehicle permitting said tower to be swung in any direction, either towards or away from the building, that is, in a direction transverse to the length of the vehicle, or in a direction more or less in a line with the vehicle, when, for example, it is desired to train the several nozzles, or

principally the nozzle 5 upon any one of a series of windows on the same floor. When traveling towards and from the fire, the tower is usually held in an upright position, so that no time need be lost in raising the tower upwardly after the scene of conflagration has been reached, and in the present instance, I have shown, for the purpose of holding the tower in any desired direction when elevated, a series of diverging props, each of which consists of a member 21 secured pivotally at one end to the base section of the tower and another member 22 in which the member 21 telescopes, the several members 22 being secured to the bed of the vehicle in any desired manner.

Clamps 23 which may be of any design or construction are designed to bind the two sections 21 and 22 together at their proper extended position, to hold the tower securely.

As has been before indicated, it is my purpose to have the tower and fireman's elevator leaned towards the burning building after the apparatus has reached the scene, and to also have the device susceptible of being swung in a direction coincident with the length of the vehicle, which is, for instance, drawn up along side of the curb. For the purpose of leaning or inclining the tower and elevator in either of these directions or for obtaining the proper inclination, in any direction on the ball and socket joint before set forth, I have provided two winches 24 and 25 mounted on the bed of the vehicle 18 and preferably at right angles to each other. In the present instance, for example, I have selected the rear end of the vehicle for the winch 24 and one adjacent side for the winch 25. A cable 26 is secured to the base section 1, or other desired portion of the tower, and passes under and around the pulley 27 secured to the bed of the vehicle as shown. This cable then winds in one direction around the winch 24. Another cable 28 is also secured to the tower and diverges from the cable 26 and passes under and around another pulley 29, being finally wound around the winch 24 in a direction reverse to the direction of winding the cable 26. Hence it will be understood that by winding the winch in one direction the cable 26 will be wound up on the winch, while the cable 28 is unwound therefrom, such operation effecting a swinging movement of the tower away from the building which is at that time on the right hand side of the vehicle, as it is viewed from the rear. Conversely, the opposite rotation of the winch will swing the tower, manifestly, towards the building. A cable 30 is secured to the tower and passes around a pulley 31 and winds around the winch 25 in one direction, and a similar cable 32 is secured to the tower and diverges downwardly from the cable 30

and extends around the pulley 33, being finally wound around the winch 25 in a direction opposite to the direction of winding the cable 30. Hence, it will be seen that by winding the winch 25 in one direction or the other, the tower may be leaned either rearwardly or forwardly. By manipulating both of the winches any inclination of the tower may be effected.

In addition to its function as a water tower, it is to be understood that my apparatus combines the usefulness of an elevator adapted to raise the firemen to the desired height and to then have the tower lean towards the building so that the firemen may enter upon one or the other of the floors. For this purpose a platform 34 is supported by the tower. Fig. 2 illustrates the fact that the firemen may be raised on the platform with the fire fighting apparatus, and Fig. 1 illustrates the apparatus at the limit of its extension, with the firemen standing on the platform. The platform 34 is provided with a railing 35. The platform 34 is pivotally mounted upon the uppermost section of the tower, so as to swing about a horizontal axis in one plane, as indicated at 36, this being manifestly essential, so that the platform may be held in a substantially horizontal position, irrespective of the inclination of the tower necessary to bring the platform to a position where the firemen may pass therefrom into the window or the like.

In order to swing the platform 34 to the proper plane as regards the tower when the tower is inclined, and to hold the platform at the proper adjustment relative to the tower, I have provided the following parts: A collar 37 is clamped around the uppermost section 35 and formed with a curved locking bar 38 which preferably extends up through a slot in the platform and which is provided with a series of sockets or apertures 39. A lever 40 is fulcrumed on a brace 34^a secured to and depending from the platform at one side of its pivot, and said lever is pivotally mounted on the same pivot as the platform and is provided at one end with a sleeve 41 which receives the curved locking bar 38 and which is provided with an aperture through which the locking detent 42 projects so as to penetrate or pass through one of the sockets or apertures 39. The free end of the detent and the free end of the lever extend across the pivot point of the platform and upwardly through the latter, as best shown in Fig. 3, so that any fireman may retract the detent, and positively or manually swing the platform to its required adjustment, and then may release the detent so as to effect a locking engagement between the lever (and platform) and the locking bar 38.

In order that the firemen may carry a line of hose into the burning building from an elevated floor, without the necessity of labori-

ously climbing the ladder, a reel 43 is mounted on one side of the vehicle bed, and a hose 44 is adapted to unwind from the said reel, as the tower and elevator are extended upwardly, the said hose carrying a nozzle 45 and being provided, preferably just below the nozzle, with a snap hook 46, adapted to be caught into a loop 47 projecting from one edge of the platform 34.

It is obvious that it may become necessary for firemen to ascend or descend from the platform 34 after the latter has been elevated, and I have therefore mounted a ladder reel 48 on the vehicle bed. A flexible ladder 49 preferably of asbestos and wire intertwined, is designed to unwind from said reel 48, as the platform 34 is carried upwardly, the upper end of said ladder being provided with hooks 50 taking into eyes 51 projecting from another edge of the platform 34. 52 designates guys that may be secured in any way in the platform and which may be used in an evident manner to assist in holding the devices in a perfectly rigid position, when either elevated or lowered.

As illustrated in Fig. 7, I may provide each tubular section of the tower, preferably just below the collar at the upper end thereof and below the next adjacent inner section when the sections are extended, with an outlet 53 to which may be attached a monitor nozzle with a handle for manipulating the same, or a hose, as desired. This is for the purpose of supplying a stream of water to the fire that may be below the point to which the tower has been raised. By this arrangement, it will be noted that I have provided a water tower from which a fire may be fought from various heights simultaneously.

From the foregoing description in connection with the accompanying drawings, it will be seen that I have provided a very efficient fire fighting apparatus which combines a water tower with an elevator for raising firemen and their fire fighting accessories to an elevated position where their work can be effectively accomplished, and that by the use of my apparatus, several "pieces" of apparatus can be dispensed with, this being a desideratum, because it not only effects economies in the cost and maintenance of a fire department, but promotes the efficiency of the same.

Having thus described the invention, what is claimed as new is:

1. In an apparatus of the character described, the combination of an extensible water tower, means for extending the same, an elevating platform carried by the tower and mounted to tilt thereon about a horizontal axis, a locking bar carried by the tower, and a hand lever pivotally connected to the axis of the platform and to the latter at one side of the axis, the free end of said lever extending upwardly through the platform at

the opposite side of said axis, said lever being provided with a detent designed for locking engagement with the locking bar.

2. In an apparatus of the character described, the combination of an extensible water tower, a platform carried thereby, means for extending the tower, the platform being pivotally mounted on the tower to swing about a horizontal axis thereon, a curved locking bar secured to the tower and projecting therefrom, a pivoted locking lever connected to the platform, and a detent carried by the locking lever and designed for locking engagement with the locking bar.
10. 3. In an apparatus of the character described, the combination of an extensible water tower, a platform carried thereby, means for extending the tower, the platform being pivotally mounted on the tower to swing about a horizontal axis thereon, a locking bar secured to the tower and projecting outwardly and upwardly therefrom, the tower being formed with a slot through which the upwardly extending portion of the locking bar projects, a locking lever pivotally connected to the platform at the axis thereof, the platform being formed with a slot through which one arm of said lever extends upwardly, the locking bar being formed with a series of apertures and the lever being formed with a sleeve encircling the locking bar, and a detent pivotally mounted on the lever and having one end arranged to extend through the sleeve into locking engagement with any of the apertures of the locking bar.
4. In an apparatus of the character described, an extensible water tower comprising telescopic sections, a support therefor, a universal joint connection between the lowermost section of the tower and the support, winches mounted on the support, two diverging cables for each winch secured to the lowermost section of the tower and winding in opposite directions on the coöperating winch, and pulleys mounted on the support and with which the divergent portions of the cables are engaged, as and for the purpose set forth.
50. 5. In an apparatus of the character described, an extensible water tower comprising telescopic sections, a support therefor, a universal joint connection between the tower and the support, winches mounted on the

support, substantially at right angles to each other, two pairs of diverging cables secured to the lowermost section of the tower and winding in opposite directions on the respective winches, and pulleys mounted on the support and with which the divergent portions of the cables have engagement, as and for the purpose set forth.

6. In an apparatus of the character described, a water tower comprising a series of telescoping sections, means for automatically locking said sections in extended position, said means consisting of spring pressed elements, the several sections being provided with recesses for the reception of said elements, and means for manually retracting said elements from the recesses.

7. In an apparatus of the character described, a water tower comprising a series of telescoping sections, means for automatically locking said sections in extended position, said means consisting of inwardly spring pressed blocks, the several sections being provided with recesses in which the blocks are adapted to spring, and means for retracting said blocks from the recesses.

8. An apparatus of the character described, comprising a series of telescoping tubular sections, means for extending said sections, and curved clamps extending through the respective sections into engagement with the next adjacent inner section, and adapted to hold the sections at different extended positions, the said clamps being provided with roughened inner faces and with swiveled actuating screws, substantially as shown and described.

9. An apparatus of the character described, comprising a series of telescoping tubular sections, means for extending said sections, means for automatically limiting the outward movement of said sections with respect to each other, and manually operable clamps extending through the respective sections into frictional engagement with the next adjacent inner section whereby the sections may be held at any desired extension short of the automatic limiting means.

In testimony whereof I affix my signature in presence of two witnesses.

SOLOMON GERMAN. [L. S.]
